UNITED STATES PATENT OFFICE

124,351

DESIGN FOR A GAME DEVICE FOR AN AMUSEMENT MACHINE CABINET

Harry E. Williams and Lyndon A. Durant,
Chicago, Ill.

Application March 30, 1940, Serial No. 91,356

Term of patent 3½ years

To all whom it may concern:

Be it known that we, Harry E. Williams and Lyndon A. Durant, both citizens of the United States and both residents of Chicago, in the county of Cook and State of Illinois, have invented a new, original, and ornamental Design for a Game Device for an Amusement Machine Cabinet, of which the following is a specification, reference being had to the accompanying drawing, forming a part thereof, and in which:

Fig. 1 is a top plan view of a game device for an amusement machine cabinet showing our new design; and

Fig. 2 is a sectional view of the same, taken on line 2—2 in Fig. 1.

We claim:

The ornamental design for a game device for an amusement machine cabinet, as shown.

HARRY E. WILLIAMS.
LYNDON A. DURANT.
